ROAD MACHINE

Carl A. Gustafson, Minneapolis, Minn., assignor
to Caterpillar Tractor Co., San Leandro, Calif.,
a corporation of California

Application October 12, 1932, Serial No. 637,464

1 Claim. (Cl. 37—156)

The present invention relates to road machines and particularly to automotive road machines having a plurality of earth engaging tools which are adjustable by power control means 5 driven from a source of power which also supplies power for propelling the machine.

It is an object of the invention to provide a transmission including a clutch-controlled drive and a constantly running drive.

10 Another object of the invention is to provide a power take-off means constantly driven from the crankshaft of a motor.

Another object of the invention is to provide 15 a clutch-controlled drive and a constantly running drive having the same axis of rotation.

Another object of the invention is to provide 20 a clutch-controlled hollow drive shaft for propelling a machine and a constantly running power take-off shaft extending through the hollow shaft.

Another object of the invention is to provide 25 separate clutch-controlled drives from a source of power, certain portions of said drives being co-axial.

Another object of the invention is to provide 30 improved means for adjustably supporting an earth engaging tool from a frame.

Another object of the invention is to provide 35 supporting means for the tool of a road machine in which vertical and horizontal play is eliminated.

Another object of the invention is to provide 40 an earth engaging tool which is adjustable to vary the angle between said tool and the surface of the earth.

Another object of the invention is to provide 45 power operated mechanism for adjusting the earth engaging tools of a road machine.

Another object of the invention is to provide 50 an automotive road machine having a power unit which supplies a constantly running drive for operating the tool adjusting mechanisms and a clutch-controlled drive for propelling the machine.

45 Other objects will appear as the description progresses.

Description of figures

Fig. 1 is a side elevation of the machine, the 50 front end being broken away to show the draft connection for the tool.

Fig. 2 is a plan view, certain parts being broken away at the front end to show the draft connection for the tool.

55 Fig. 3 is a longitudinal, vertical section through

the clutch, the transmission, motor, and rear axle assembly being shown in phantom lines.

Fig. 4 is a rear view of the blade and circle assembly.

Fig. 5 is a side elevation of the blade and circle 5 assembly, with certain parts broken away to disclose the means for shifting the circle on its center.

Fig. 6 is a section on the line 6—6 in Fig. 5.

Fig. 7 is a section on the line 7—7 in Fig. 5. 10

Fig. 8 is a section on the line 8—8 in Fig. 2.

Fig. 9 is a plan view of the blade and circle assembly.

Fig. 10 is a section on the line 10—10 in Fig. 9. 15

Fig. 11 is a plan view on the line 11—11 in Fig. 10.

Fig. 12 is a section on the line 12—12 in Fig. 9.

Fig. 13 is a section illustrating the construction 20 of the lift hangers.

Fig. 14 is a view on the line 14—14 in Fig. 13. 25

Fig. 15 is a view on the line 15—15 in Fig. 13.

Fig. 16 is a view on the line 16—16 in Fig. 15.

Fig. 17 is a longitudinal, vertical section 30 through the scarifier.

Fig. 18 is a longitudinal, vertical section through the power control clutch mechanism.

Fig. 19 is a diagrammatic view illustrating the power control clutch mechanism, the drive therefor, and the connections therefrom to the adjusting means for the blade and scarifier. 35

Description of machine

Road machines having power operated mechanism for controlling the adjustment of the earth moving means thereof have heretofore been provided with different sources of power for propelling the machine and for driving the power control mechanism, or, where the same source of power is used for both purposes, the driving means for the power control mechanism is connected to the clutch driven shaft which also drives the transmission mechanism. The use of the same source of power for both purposes possesses obvious advantages over the provision of different sources of power but where the clutch driven shaft serves to drive the power control mechanism, as in the machines heretofore known, certain disadvantageous features result. 40

The principal disadvantage is that the power take-off for the power control mechanism can 50 be driven only when the clutch is engaged, and, consequently, the power control mechanism can not be operated while the clutch is disengaged in shifting gear, or in stopping and starting the machine. Moreover, when the machine is not in 55

motion and the power control mechanism is being used, any accidental movement of the gear shift lever results in a sudden starting of the machine as the clutch is engaged. Such sudden movement of the machine is not only very apt to cause breakage of parts, but is also very dangerous to the operator.

These disadvantages are eliminated by the invention disclosed herein which provides a constantly running power take-off drive for the power control mechanism and a clutch-controlled drive for the traction devices of the machine. Thus the drive for the power control mechanism is never interrupted by the operator in driving the machine but is always available irrespective of the engagement or disengagement of the clutch. Furthermore, any danger to the operator or machine from accidental starting is eliminated.

The feature of the invention referred to above is equally useful in other road machines which are not self-propelled such as an elevating grader having a source of power providing a clutch-controlled drive to operate the carrier belt and having power control mechanism for the plow and/or the carrier. The invention is also applicable to tractors provided with a power take-off used in connection with drawn vehicles such as road machines and harvesters, or with mechanisms adapted to be mounted on the tractor such as hoists, bulldozers, agricultural implements, etc., having parts adapted to operating by power.

Frame and supports therefor

The frame of the machine is substantially symmetrical with respect to the longitudinal axis thereof and includes two side channels 10, 11 (Figs. 1 and 2) which extend substantially the length of the machine and have a slight convergence toward the front end (Fig. 2). These side channels are connected by cross members and braces. In the front end of the machine bolster 12 is riveted to the forward ends of side channels 10 and 11. Said bolster 12 is provided with bearings 13, 14 forward of the front ends of side channels 10, 11, which receive a shaft providing a draft connection for the scarifier as described hereinafter. Said bolster 12 is also provided with centrally located bearing 16 (Fig. 1) on the under side thereof which is adapted to receive a draft connection for the tool as described hereinafter.

Near the front end, hanger 17 (Fig. 1) is provided, the ends thereof being riveted to side channels 10 and 11, respectively, suitable gussets serving to strengthen the connections. Said hanger 17 supports certain braces as hereinafter described.

At the rear end of the machine, side channels 10, 11 are secured to curved channel 21 by suitable brackets, said channel forming a rear bumper. Toward the front end of the machine above the scarifier, I-beam 31, (Fig. 2) forms a cross-piece between side channels 10, 11, being secured thereto by gussets 32.

Above the blade, brackets 36, 37 are secured to side channels 10, 11, respectively, and serve to support the blade lifting mechanism. Angle 38 connects said brackets 36, 37, at the top, and at the bottom said brackets are connected by a similar cross angle which has T-bar 41 (Fig. 1) secured thereto. T-bar 41 supports the center shift mechanism.

Dashboard 56 (Fig. 2) at the operator's station

supports the power control mechanism, and cross angle 48, therebeneath, supports a portion of the drive connection from the motor to said power control mechanism. Said dashboard 56 and cross angle 48 are secured to side channels 10, 11, by vertical angles forming part of the framework at the operator's station. Steerable supports are provided at the front of the machine and driving supports are provided at the rear. The frame is strengthened by a plurality of suitable cross braces. The front supports comprise wheels 100, 101 (Fig. 2) journaled on spindles integral with knuckles 102, 103, respectively, which are pivotally secured to the respective ends of front axle 104. At its center, axle 104 pivotally supports casting 109 (Fig. 1) which is bolted at its upper end to bolster 12. Said casting 109 is provided with bearing 112 adapted to receive a draft connection for the blade.

Brace rods 116, 117 (Fig. 2) are secured to axle 104 at their forward ends and converge rearwardly to hanger 17 (Fig. 1), having a common pivotal connection 118 therewith.

Steering arms 126, 127 (Fig. 2) are secured to knuckles 102, 103, respectively, and the rearward ends thereof have a pivotal connection with the respective ends of adjustable tie rod 128. Arm 127 has lateral extension 129 having a ball and socket connection with drag link 131 (Fig. 1). Said drag link 131 has a ball and socket connection with arm 132 which is operated by steering mechanism enclosed in housing 133 (Fig. 2) bolted to side channel 11. Said steering mechanism may be of the type disclosed in Patent 1,618,588, issued February 22, 1927, to Edward Hassig. Shaft 134 journaled in housing 133 and adapted to operate the steering mechanism has universal joint 136 with shaft 137 journaled in bearing support 138 on angle 38 and similar bearing support 139 on power control clutch housing 1128. Handwheel 143 is secured to shaft 137 for operating the steering mechanism. Said bearing support 138 (Fig. 8) comprises bearing sleeve 141 engaging said shaft and pivoted by pin 142 in opposite ears 143 on tubular support 144. Said support 144 is slidable in bracket 145 bolted to cross angle 38 and said bracket is slotted vertically at 146 to form with clamping bolt 147 a means for clamping said bearing support 144 in its vertically adjusted position. Said bearing support 139 is similarly constructed.

From the foregoing description it is seen that steerable front supports are provided for the machine and that the control shaft for operating the steering means is journaled in pivotally mounted, vertically adjustable supports.

The rear end of the frame is supported on traction devices comprising rear wheels 200, one of which is shown in Fig. 1. Said wheels 200 are mounted on the rear axle supported in a rear axle housing suitably connected to side channels 10, 11. The drive for rear wheel 200 is described herein-after.

Power unit

The power unit comprises the motor, clutch, and transmission mechanism, the crankcase of the motor and the clutch and transmission housing being secured together and mounted on the rear axle housing.

Motor 300 (Fig. 3) may be of any suitable type, and is here shown as an internal combustion engine. Crankcase 302 is supported on rear axle housing 221 at 301, and is bolted at its forward end to clutch and transmission housing 303, having

ing a rearward opening conforming to the front opening in said crankcase. Said housing 303 is provided with front cover plate 307 extending substantially the full length thereof and bolted thereto. The lower rearward portion of housing 303 is bolted to rear axle housing 221, said housings having conforming openings. Thus it is seen that crankcase 302, and clutch and transmission housing 303 are rigidly secured together 10 as a unit and are connected to rear axle housing 221.

The front power unit support comprises cross angle 76 suitably secured to side channels 10, 11 at its ends. Adjacent to and just above said angle 15 76, block 316 is secured to cover 307 by cap screws 317. Said block 316 is supported on cross angle 76 by rubber block 318 and shim 319, being held thereon by cradle 321. Rubber block 322 is interposed between the top of said block 316 and 20 said cradle 321. Bolts 323 passing through the feet of cradle 321, shim 319 and the horizontal flange of angle 76 secure said cradle to said angle. From the foregoing description, it is seen that the front of the power unit is resiliently supported 25 in the frame for limited movement with respect thereto.

The controls for motor 300 are located at the operator's station. Throttle control lever 331 (Fig. 2) is suitably mounted on the left end of 30 power control clutch housing 1128. Bracket 333 bolted to the right end of said housing 1128 provides a support for manifold heat control lever 334 and the ignition switch (not shown).

Clutch and transmission

35 Clutch 400 (Fig. 3) transmits two drives from the motor, a controllable drive to the transmission as determined by the clutch pedal located at the operator's station, and a constant drive to the power control mechanism, which is described in a subsequent section.

Crankshaft 336 of motor 300 is secured at its rear end to flywheel 401 by bolts 402 passing through said flywheel and flange 337 on said 45 crankshaft. Flywheel 401 is provided with a cylindrical flange 403 to which centrally apertured plate 404 is bolted. Levers 405, only one of which is shown, pivoted on plate 404 extend substantially radially thereof and are provided at their 50 outer ends with fingered apertures adapted to receive bolts 406 which pass through apertures in plate 404 and are pivoted to plate 407. Springs 408 surrounding bolts 406 tend to hold said levers 405 in the position shown in Fig. 3. Plate 407 is 55 provided with teeth which mesh with internal teeth formed on flange 403 of flywheel 401, whereby said plate 407 rotates with said flywheel 401 but is shiftable with respect thereto. A plurality of compression springs 409 are provided, only one 60 of which is shown, which press plate 407 towards said flywheel 401, said springs 409 being seated in cups 411 formed in plate 404, and engage projections 412 on plate 407.

Plate 413 is riveted to hub 414 splined on tubular shaft 416 and is provided with clutch faces 417 of suitable composition, said faces 417 being adapted to be engaged by the respective clutching faces of flywheel 401 and plate 407.

From the foregoing description, it is seen that 70 when levers 405 are in the position shown in Fig. 3, springs 409 press plate 407 inwardly whereby clutch faces 417 on plate 413 are gripped between the respective clutching faces of flywheel 401 and plate 407, transmitting the drive therefrom to hub 75 414 and tubular shaft 416. Said shaft 416 is sup-

ported in flywheel 401 by bearing 418 having bearing retainer 419, passes through sleeve 420, mounted in housing 303, and is supported at its forward end in plate 307 by bearing 421 mounted in bearing cage 422. Bearing 421 is held in cage 422 by spacer 423 and bearing adjusting nut 424 having threaded engagement with said shaft 416. Said nut 424 holds bearing 421 in engagement with a shoulder on shaft 416, and the flange of cage 422 in engagement with housing 303. 10

Gear 426 is keyed on tubular shaft 416 between bearing 421 and oil thrower 427 adjacent collar 428 of shaft 416 which holds sleeve 420 in place. Said gear 426 meshes with gear 429 mounted on bearings 430 on stub shaft 431. Lock nut 432 15 threaded on shaft 431 holds said bearings in place. Said shaft 431 is mounted in apertured boss 433 of clutch and transmission housing 303. Gear 429 meshes with a suitable gear on driving transmission shaft 503 whereby the transmission is 20 driven from clutch-controlled shaft 416.

It is seen, therefore, that the drive for driving transmission shaft 503 is controlled by movement of plate 407 of the clutch 400 as determined by movement of levers 405. The inner ends of levers 25 405 bear against the face of thrust ring 436 surrounding tubular shaft 416 but not engaged therewith. Ring 436 is mounted in bearing cage 437 by bearing 438, being held therein by the end of levers 405. Oil retainer 439 engages cage 437 30 and ring 436.

Cage 437 is slidably mounted on sleeve 420 and is held resiliently against the wall of housing 303 by compression springs 441 surrounding studs 442 held between flange 443 of said cage 437 and 35 washers 444 on the ends of said studs 442, which pass freely through said flange and have threaded engagement with the wall of housing 303. Cage 437 when moved forwardly presses ring 436 against the inner ends of levers 405 whereby said 40 levers are rocked to move plate 407 to the right as viewed in Fig. 3, thereby interrupting the drive for driving transmission shaft 503. 40

Movement of cage 437 and ring 436 is controlled by a pair of arms 451 of yoke 452 which is keyed 45 and clamped on shaft 453. Said arms engage the opposite sides of cage 437, left arm 451 being shown in Fig. 3. Shaft 453 is journaled in housing 303 and extends therethrough to the left of the machine. Arm 459 (Fig. 1) secured to shaft 453 50 outside of housing 303 is urged to clutch engaging position by spring 460 secured thereto and said arm is pivotally connected at its upper end to adjustable rod 457. Said rod 457 is pivotally connected at its forward end to short arm 458 integral 55 with sleeve 459 of clutch pedal 461. Said sleeve 459 is loosely journaled on a shaft suitably supported on respective side channels 10, 11.

It is obvious from the foregoing description that 60 operation of the clutch pedal serves to engage and disengage the clutch to transmit a drive to the transmission as controlled by the operator.

The transmission mechanism is illustrated in 65 phantom lines in Fig. 3 and comprises driving transmission shaft 503 having a plurality of gears 504 thereon and driven transmission shaft 502 having a plurality of shiftable gears 505. Said transmission shafts 502, 503, and clutch driven shaft 416 lie in substantially the same vertical 70 plane. The transmission mechanism serves to transmit forward and reverse drives of varying speeds to the rear axle and wheels. This mechanism may be of the type disclosed in the co-pending application of Oscar L. Starr, Serial No. 75

631,050, filed August 30, 1932. The transmission mechanism is controlled by gear shift lever 632 (Fig. 2) in a manner fully disclosed in said application. Brake means 668 (Fig. 3) is associated with driven transmission shaft 502, brake pedal 694 (Fig. 2) controlling the operation thereof.

Thus it is seen that a clutch controlled drive from the power unit is provided for propelling the machine, and, as described hereinafter, the power unit also provides a constantly running drive for the power control mechanism.

Blade and circle

Blade 703 (Figs. 4 and 5) consists of a cutting edge comprising two cutting sections 701 secured to moldboard 702 by bolts 703, which also serve to secure angle 704 thereto. Angle 706 is riveted to the trailing edge of angle 704. Reference numeral 707 indicates suitable flag sockets. Brackets 708 serve to connect the blade to the circle in a manner hereinafter described.

Circle 711 (Fig. 9) is made of a single piece of angle bent into a circle with the ends joined by welding, but said circle may be formed in any other suitable manner. Beam 712 is provided with central portion 713 bent into a semi-circle of substantially the same radius as the circle, and said central portion 713 encompasses approximately one half of circle 711 and is riveted thereto. End portions 714, 716 (Fig. 4) of the beam extend tangentially from the circle and downwardly, their lower ends being apertured for connection to brackets 708 by means of bolts 717. These connections are similar and only one will be described. Bolt 717 (Fig. 6) is journaled in tapered sleeve 718 which engages complementary aperture 719 in end portion 716. Washer 721 is held between end portion 716 and nut 722 threaded on bolt 717.

In order to rigidly connect the end portions of the beam to the circle, brackets 726, 727 (Fig. 4) are riveted to respective end portions 714, 716. The upper ends of brackets 726, 727 are riveted to the ends of cross angle 728 which is rigidly connected to the circle by brackets 729, 731. In addition, the lower ends of brackets 726, 727 are rigidly secured by gussets 732, 733 to the lower ends of inclined braces 734, 736, the inner ends of which are riveted to angle 728.

Blade 708 is angularly adjustable about the axis of bolts 717 to alter the inclination of cutting edge to the surface of the ground. To lock the blade in adjusted position, links 737, 738 (Fig. 9) are connected by bolts 739, 741 to brackets 742, 743, respectively, on moldboard 702. As shown in Fig. 7, link 738 is provided with tapered hub 744 which pivots on complementally formed conical boss 745 on bracket 743. Link 737 and bracket 742 are similarly connected. The inner faces of links 737, 738 are serrated (Fig. 9) to engage corresponding serrations in clamping blocks 746, 747 on the beam, being held engaged therewith by bolts 748, 749.

The circle is revolvably mounted in a framework consisting of forwardly converging drawbars 751, 752, rear cross angle 753, and yoke 754. Rear cross angle 753 is connected to the rear ends of drawbars 751, 752 by brackets 756, 757 bolted thereto. Yoke 754 is bolted to drawbars 751, 752 intermediate their ends.

The inwardly extending flange of circle 711 (Figs. 10 and 11) rests on arcuate ledge 758 of shoe 759 which is bolted to bracket 757 by bolts 760 passing through elongated apertures 761 in

said shoe 759. Above ledge 758 a portion of bracket 757 extends over the inwardly projecting flange of circle 711 where it is provided with recessed boss 762 adapted to receive rub iron 763. Adjusting screw 764 for said rub iron is threaded in boss 762 and is provided with lock nut 765. Said shoe 759 is provided on its inner edge with flat surfaces 766 which are engaged by adjusting screws 767 threaded in bosses 768 in bracket 757 and having lock nuts 769. The arcuate ledge provides a support for the circle on which the circle can be revolved and the rub iron serves to take up wear in parts and reduce the amount of play between the circle and the support. The adjustable shoe is movable radially of the circle by the adjusting screws within the limits of the slots in said shoe and serves to take up the side play between the circle and its support. Bracket 756 is similarly equipped, having parts identical with those illustrated in Figs. 10, 11 in connection with bracket 757.

Yoke 754 (Fig. 12) is provided at its left front corner with arcuate ledge 770 upon which the inwardly extending flange of circle 711 rests. Boss 771 in the overhanging portion of yoke 754 receives rub iron 772 having adjusting screw 773 threaded in said boss and provided with lock nut 774. Yoke 754 is similarly equipped at the right front corner.

Thus, four arcuate ledges, arranged in a circle, 30 are provided on the circle supporting framework which permit the circle to be revolved thereon, and there is an adjustable rub iron associated with each support. The two rear supports include adjustable shoes to take up side play. 35

From the foregoing description it is seen that the circle is revolvably supported at four points, two of these being at the front in yoke 754 which is provided with adjustable rub irons, and two in the rear where brackets 756, 757 are provided 40 with adjustable rub irons and adjustable shoes. The circle, therefore, can be rotated about its center, and means are provided for taking up play between the circle and its supports in both vertical and horizontal directions. 45

Drawbars 751, 752 converge forwardly to connection 777 (Figs. 1 and 2) to which they are bolted. Bolt 778 in connection 777 is provided with apertured head 779 which receives pin 781 journaled in universal connection 782. Nut 783 is threaded on bolt 778. Universal connection 782 (Fig. 1) is journaled in bearing 16 in yoke 12 and bearing 112 in casting 109. Thus drawbars 751, 752 can pivot in a vertical plane about the axis of pin 781, can pivot in a horizontal 55 plane about the axis of universal connection 782, and can rotate about the axis of bolt 778. It is seen, therefore, that the drawbar circle assembly is capable of a limited universal movement about the intersection of the axes of pin 781 and connection 782 as a center. 60

To summarize the movements of which the circle is capable they are, an arcuate movement in a horizontal plane about the vertical axis of universal connection 782; an arcuate movement 65 in vertical planes containing the axis of connection 782; oscillation about the axis of bolt 778; and oscillation of the circle about its center. The desired circle adjustment is usually obtained by combinations of these movements. 70

Blade lift

Telescopic lift hangers are provided for adjustably supporting the blade and circle assembly from the frame. 75

The ends of rear cross angle 753 (Figs. 5, 9 and 13) are connected by ball and socket connections 800-801 to lift screws 802, 803, respectively. As the lift hangers are identical in construction, only one will be described in detail, and the right-hand hanger which includes screw 803 will be referred to. Ball and socket connection 801 (Fig. 13) comprises ball 804 welded at 806 to angle 753, and a socket formed by the end of screw 803 and cap 807 (Figs. 13 and 14), bolts 808 serving to connect said cap 807 to said screw 803. Screw 803 telescopes within tubular shield 809 which is welded at 811, 812 (Fig. 13) to lower section 813 of housing 814. Wiper 816 (Figs. 13 and 14) at the lower end of shield 809 has an outward flange which is held between the end of said shield and an inward flange on clamp 817, having clamping bolts 815. Said clamp 817 has a pair of opposite fingers 818 (Fig. 14) adapted to engage the heads of bolts 808 of ball and socket connection 801 to limit upward movement of lift screw 803.

Said lower section 813 (Fig. 16) of housing 814 is formed as an inverted T at its lower end, extensions 819 thereof being cylindrical and having bushings 821 journaled therein (Fig. 15). Trunnions 822 journaled in said bushings 821 are also journaled in apertured arms 823 of fork 824. Bolts 826 (Figs. 15 and 16) passing through apertured bosses 827 in said arms 823, engage peripheral grooves 828 in said trunnions 822 to hold them in place. Said trunnions are longitudinally apertured to provide lubricant passages.

Journal 829 (Fig. 13) of fork 824 is mounted for rotation in bushing 831 mounted in apertured boss 832 in arm 833 (Figs. 13 and 15) of bracket 37. Nut 834 threaded on the reduced end of journal 829 presses washer 836 into engagement with boss 832 and holds flange 831 of fork 824 in engagement with flange 838 of boss 832. Pin 839 locks nut 834 in adjusted position.

From the foregoing description it is seen that lift screw 803 is capable of pivotal movement about the axis of trunnions 822, and is also capable of pivotal movement about the axis of journal 829 of fork 824. Thus said lift screw 803 is mounted for universal movement about the point of intersection of the axes of trunnions 822 and journal 829.

The upper end of screw 803 is received within cylindrical shield 841 (Fig. 13) which is closed at its upper end, and which is of sufficient length to permit movement of screw 803 through its total range of movement. Said shield 841 is welded at 842 to collar 843 which has threaded engagement with the upper section 844 of housing 814. Said upper section 844 is secured to said lower section 813 by bolts 845 (Fig. 2). Opposite apertured bosses 846 (Fig. 13) of collar 843 provide means for turning said collar for a purpose to be described later.

Upper section 844 of housing 814 is slotted at 847 and is provided with opposite apertured bosses 848 which receive clamping bolt 849 which serves to hold collar 843 in adjusted position.

Within housing 814 internally screw threaded collar 851 (Fig. 13) is mounted on bearing 852 seated in recessed seat 853 in lower section 813 of said housing 814. Washer 854 is seated in upturned flange 856 of collar 851 and is received in upper section 844 of housing 814, abutting the lower end of collar 843. Thus it is seen that

collar 843 serves as an adjusting means to prevent longitudinal movement of collar 851 with respect to housing 814 whereby said collar 851, upon rotation thereof, will raise or lower screw 803 which has threaded engagement therewith. 5

Bevel gear 857 is secured to the lower end of collar 851 by pin 858 and the hub of said gear 857 extends below collar 851 to engage bearing 852. Bevel gear 857 meshes with and is driven by bevel pinion 859 secured to stub 10 shaft 861 by key 862 and held thereon by nut 863.

Stub shaft 861 is journaled in bracket 864 bolted to housing 814. Fork 867 is keyed to the outer reduced end of stub shaft 861 by key 868 (Fig. 13), 15 being held thereon by nut 869. Thus it is seen that rotation of fork 867 and shaft 861 in one or the other direction through bevel pinion 859 and bevel gear 857 serves to raise or lower screw 803 whereby the right end of blade 700 is raised or 20 lowered correspondingly.

Brace facing 871 (Fig. 13) is riveted to the face of hub 872 of fork 867 and engages washer 873 seated within cup 874 formed in bracket 864. A pair of compression springs 876 are seated in recessed bosses 877 of cup 874 and engage washer 873 to urge it into contact with brace facing 871. Seal 878 engages stub shaft 861 and is seated in bracket 864. The braking means described above, comprising brake facing 871 and washer 873, 30 serves to prevent movement of the blade and circle assembly from their adjusted position.

While collar 851, comprising the nut, and lift screw 802 are irreversible, a very small force is required to turn said collar 851 to lower lift screw 35 802 when the blade is disengaged from the earth, and conversely to raise lift screw 802 when the blade is engaged with the earth. It has been found that the accidental rotation of stub shaft 861 due to vibration thereof is sufficient to turn 40 collar 851 under the above described conditions thereby destroying the adjustment of the blade. The frictional engagement of brake facing 871 with washer 873 damps vibration of said shaft 861, and prevents rotation thereof due to such vibration. 45 Thus any unintentional rotation of collar 851 is prevented, and the adjustment of the blade is maintained.

Lift screw 802 (Fig. 4) is similarly mounted in housing 881 (Fig. 2) which is universally mounted 50 on arm 882 of bracket 36 in the same manner that housing 814 is mounted on arm 833 of bracket 31. Fork 883 (Fig. 2) of universal joint 1197 drives screw lift mechanism for screw 802 which is identical in construction with that described above for 55 lift screw 803.

It is seen, therefore, that the blade and circle assembly can be simultaneously raised or lowered at both ends, or either end thereof may be adjusted to a different height from the opposite end. 60

Circle shift

Means are provided for (1) shifting the center of the circle transversely of the machine or about the axis of universal connection 182 (Fig. 1) and 65 (2) shifting the circle on its own center.

(1) For shifting the center of the circle, the supporting frame of the circle is adapted to be connected by a link to a rack on the main frame which can be slid transversely thereof. Rear 70 cross angle 753 (Fig. 4) of the circle supporting frame is provided with aperture 901 having boss 902 welded around its periphery. Said aperture 901 receives the lower bent end of link 903, the upper bent end thereof being received in apertured 75

lug 904 (Fig. 1) depending from rack 906. Said rack 906 has channels formed integrally therewith for engagement with the flanges of T-bar 41, which, as explained before, is secured to the main frame.

Rack 906 is adapted to slide along bar 41, and for this purpose is engaged with pinion 911 keyed on the lower end of vertical shaft 912 and held thereon by a nut. Said shaft 912 is journaled in housing 916 (Figs. 1 and 2) which is bolted to frame angle 38, and in a suitable bracket on T-bar 41. Within housing 916 worm wheel 921 (Fig. 19) is keyed to shaft 912 and is driven by irreversible worm 923 on shaft 924 also journaled in housing 916. Fork 926 (Fig. 1) fast on shaft 924 forms part of universal connection 1204 whereby the center shift mechanism is driven by means hereinafter described. Rotation of fork 926 and shaft 924 operates to shift rack 906 toward either side of the machine, thereby shifting the center of the circle to extend the blade farther out on either side. The lift screws alone could not maintain the blade and circle in an angular position to one side of the machine because of their pivotal connection with the circle supporting frame and the main frame, but, by the addition of the center shift lift connection, the chain of linkage comprising the main frame, lift screws 802, 803, the circle supporting frame and link 903 forms a locked kinematic chain. One of the essential characteristics of a locked kinematic chain is that when the linkage is adjusted to a selected position, it rigidly maintains itself therein. Thus the blade is maintained in any adjusted position.

(2) For shifting the circle on its center, it is provided with rack 941 (Figs. 5 and 9) formed on the horizontal flange thereof, which is engaged by pinion 942 (Fig. 5) keyed on vertical shaft 943 and held thereon by nut 944. Shaft 943 is journaled in housing 946 which is seated in aperture 945 in yoke 754, being bolted to said yoke. Worm gear 949 (Fig. 9) is secured to the upper end of shaft 943 and is adapted to be driven by irreversible worm 952 on shaft 953. Shaft 953 is also journaled in housing 946 and has fork 954 of universal connection 1209 secured to one end, and counterweight 956 secured to the other end. Counterweight 956 is formed with an unbalanced weight distribution with respect to the axis of shaft 953, and serves to damp vibration of said shaft and to prevent creeping of worm 952 due to such vibration. Fork 954 and shaft 953 are driven in a manner hereinafter described to shift the circle on its center to vary the angle of the blade with respect to the line of draft.

Scarfier

Scarfier 1000 (Figs. 1, 2, and 17) comprises block 1001 having two rows of staggered openings 1002 (Fig. 2) in the top and in the bottom thereof. The openings in the top and the bottom are aligned and provide passageways for the insertion of the scarfier teeth; the front passageways are concealed in Fig. 2. A horizontal rib 1003 (Fig. 17) is provided in said block and is disposed within said front passageways, being adapted to be engaged by any one of a plurality of notches 1004 formed on the rear face of each scarfier tooth 1005. A similar rib is provided adjacent the rear row of passageways. Wedge 1006 is driven into each opening 1002 in front of tooth 1005 to hold it firmly in position.

At its rear edge block 1001 is provided with integral pairs of vertical apertured ears 1007, 1008 (Figs. 1 and 17) for connection to apertured

ends of scarifier drawbars 1011 and 1012. As shown in Fig. 17, ear 1007 and drawbar 1011 are connected by pin 1009. Ear 1008 and drawbar 1012 are similarly connected. Said drawbars 1011 and 1012 curve upwardly and forwardly (Fig. 1) and are pivoted on the respective ends of shaft 1013 (Figs. 1 and 2) journaled in apertured bosses 13, 14 (Fig. 2) of yoke 12 previously described. Said drawbars provide a draft connection from the main frame to the scarifier.

Means are provided for varying the angle of the scarifier block with respect to the scarifier drawbars. Apertured horizontal ears 1016 (Fig. 17) and 1017 (Fig. 1), are formed integrally with block 1001 at the forward edge thereof. Ear 1017 (Fig. 1) is connected to the lower end of arm 1018 by bolt 1019. Arm 1018 is provided with a plurality of apertures 1021, and drawbar 1012 is provided with a plurality of apertures 1022 whereby arm 1018 may be selectively coupled by bolt 1023 to drawbar 1012. Ear 1016 (Fig. 17) is similarly connected to drawbar 1011 by arm 1024 (Fig. 17), similar apertures 1021, 1022 and bolt 1019 being provided. Thus the angle between the scarifier block and the drawbars can be varied to adjust the scarifier teeth angularly with respect to the surface of the ground.

Formed integrally with block 1001 at its forward edge are pairs of vertically apertured ears 1026 (Fig. 17) and 1027 (Fig. 1) to which scarifier lift arms 1028, 1029 are connected by respective pins 1031 (Fig. 1). Lift arms 1028, 1029, have ball and socket connections 1032, 1033 (Fig. 2) with levers 1034, 1036 (Figs. 1 and 2). Said levers 1034, 1036 are secured to shaft 1037 journaled in brackets 1038, 1039, bolted on gussets 32 and side frame channels 10, 11, respectively. Levers 1034, 1036 are provided at their forward ends with respective gear segments 1046, 1047, meshing with pinions 1048, 1049, keyed on respective ends of shaft 1051.

Said shaft 1051 is journaled at one end in bracket 1052 bolted to side channel 10, and at its other end in housing 1053, bolted to side channel 11. Said shaft 1051 is encased in sleeve 1054 welded within bracket 1052 and housing 1053.

Within housing 1053 worm wheel 1061 (diagrammatically shown in Fig. 19) is keyed to shaft 1051 and is driven by worm 1062 on shaft 1063 also journaled in housing 1053. Fork 1064 (Fig. 1) on shaft 1063 forms part of universal joint 1214 and is driven in a manner hereinafter described to drive the scarifier lifting mechanism above described.

Thus it is seen that upon rotation of shaft 1063 (Fig. 19) worm 1062 thereon rotates worm wheel 1061 to rotate shaft 1051. Rotation of shaft 1051 through pinions 1048, 1049 oscillates gear segments 1046, 1047 and levers 1034, 1036 to raise or lower scarifier lift arms 1028, 1029 to move the scarifier in the same manner.

Power control

Power take-off means are provided whereby a continuous drive is transmitted from the crank-shaft of the motor to the power control mechanism. Shaft 1101 (Fig. 3) journaled in bushing 1102 in the front end of tubular shaft 416 is provided at its rear end with gear 1103 meshing with internal teeth of fly-wheel 401. It is to be noted that shaft 1101, tubular shaft 416, and crank-shaft 336 have identical axes of rotation. Shaft 1101 extends through cover 1104 bolted to cover 307 and is keyed to spider 1106 of universal connection 1105. The drive is transmitted from 75

spider 1106 secured to spider 1107 by flexible disks 1109 secured to said spiders by bolts 1108. Spider 1107 is keyed on shaft 1111 which is connected to shaft 1112 (Fig. 18) by universal connection 1113, similar to universal connection 1105. One spider of said universal connection 1113 is keyed on shaft 1111 and the other is splined on shaft 1112. Said shaft 1112 enters the base of housing 1114 which is secured by bolts 1116 to angle 48. Said shaft 1112 is journaled in bushing 1117 and bearing 1118, held between split ring 1129 and the cover, shaft 1112 is held in position by collar 1119 and nut 1121 threaded thereon. Seal 1122 is seated in housing 1114 and engages said shaft.

Shaft 1112 carries worm 1123 which engages worm wheel 1124 fast on vertical shaft 1126 which extends upwardly through housing 1125 supported on and bolted to said housing 1114. Bevel gear 1127 keyed to shaft 1126 at its upper end within control clutch housing 1128, meshes with bevel gears 1131 and 1132, rotatably mounted on shaft 1133, which is journaled in bushings in housing 1128 and cover 1129 therefor. Said control clutch housing 1128, sometimes called the control box, is supported on and bolted to said housing 1125 which is located centrally with respect thereto. Said housing 1128 is also bolted at its top to dashboard 56. Thus it is seen that bevel gears 1131, 1132 are rotated in opposite directions upon rotation of shaft 1126 and gear 1127.

Hubs 1134 and 1135 of gears 1131 and 1132, respectively, are formed with beveled clutch teeth adapted to be engaged by complementary clutch teeth on double faced clutch element 1136 which engages splined portion 1137 of shaft 1133. The beveled clutch teeth provide a camming action which tends to disengage the clutch elements.

Clutch element 1136 is provided with a peripheral groove engaged by fork 1138 secured to rod 1139 slidably mounted in apertured boss 1141 in cover 1129 of housing 1128 and in boss 1142 in housing 1128. Rod 1139 is provided at its front end with peripheral groove 1143 which is engaged by ball 1144, under the influence of compression spring 1145 in a recess in said housing and seated against plug 1146 threaded therein, when said shaft is in its central position, wherein clutch element 1136 is disengaged from both gears 1131 and 1132. The aperture in boss 1142 is closed and rod 1139 is flattened at that end to permit air to pass by said rod. Spring pressed ball 1144 retains rod 1139 in its central position. Rod 1139 is pivoted at its rear end to control lever 1147. Lower rounded end 1143 of said lever 1147 is disposed within the aperture in boss 1149 on cover 1129. Thus it is seen that control lever 1147 is provided with a floating, pivotal mounting on the control box.

From the foregoing description, it is seen that upon forward movement of lever 1147 (to the right as viewed in Fig. 18) and rod 1139 pivoted thereto, fork 1138 moves clutch element 1136 into engagement with the clutch teeth on hub 1135 of bevel gear 1132 whereby said clutch element and shaft 1133 are rotated in one direction. Upon rearward movement of said lever 1147, said clutch element 1136 is engaged with the clutch teeth associated with bevel gear 1131 which serves to rotate said clutch element and shaft 1133 in the opposite direction. Spring pressed ball 1144 resists movement of lever 1147, rod 1139, and clutch element 1136 from their

central, neutral position. It is to be noted that lower end 1148 of lever 1147 moves up and down in boss 1149 as said lever is oscillated to control the reversible clutch mechanism due to the linear movement of rod 1139.

The reversible clutch mechanism described above is centrally located with respect to housing 1128 and on each side thereof two similar clutch mechanisms are provided. As shown in Fig. 18 spur gears 1151, 1157 are formed integrally with bevel gears 1131, 1132, respectively, and said spur gears comprise members of two opposite trains of intermeshing spur gears forming the driving elements of a series of reversible clutch mechanisms as illustrated diagrammatically in Fig. 19, where bevel gears 1131, 1132 are shown integrally with an end pair of spur gears for convenience in illustration. These trains of spur gears comprise spur gears 1181, 1154, 1151, 1152, 1174 and respective opposite gears 1182, 1159, 1157, 1158, 20 1175 on shafts 1183, 1156, 1133, 1153, 1176, respectively, all similar and similarly mounted in housing 1128 and cover 1129 therefor. Double-faced clutch elements 1185, 1171, 1136, 1163, 1178 are controlled by control levers 1187, 1173, 1147, 25 1167, 1180, respectively, by forks and rods similar to fork 1138 and rod 1139 (Fig. 18) and similarly mounted. Said control levers are also similar and similarly mounted.

From the foregoing description, it is seen that each of shafts 1183, 1156, 1133, 1153, and 1176 are rotatable selectively in either direction according to the movement of a clutch element controlled by forward or backward movement of a manually operated lever. It is necessary that said control levers be held in clutch engaging position as the camming action of the beveled clutch teeth serves to disengage the clutch automatically on release of said levers. If the tool encounters an obstruction, the beveled clutch teeth are disengaged automatically by the camming action despite pressure on the control levers, thereby preventing any breaking of the parts. It is to be noted that the driving elements of the above described clutch mechanism comprise a plurality of trains of constantly rotating gears, each train consisting of a series of intermeshing spur gears.

Shafts 1183, 1156, 1133, 1153, and 1176, extend through the front of housing 1128, being provided with respective oil seals similar to oil seal 1188 50 (Fig. 18) seated in housing 1128 and engaging shaft 1133. Said shafts are connected by means including telescopic shafts and universal joints to the various adjusting mechanisms heretofore described.

Shaft 1183 (Figs. 2 and 18) has universal joint 1194 with telescopic shaft 1195 which is connected by universal joint 1197, including fork 883, to the driving mechanism for lift screw 802. Thus manually operable lever 1187 controls a power drive 60 to operate lift screw 802 to raise or lower one end of the blade.

Shaft 1156 has universal joint 1201 with telescopic shaft 1202 which is connected by universal joint 1204, including fork 926 (Fig. 2) to shaft 924 65 adapted to drive worm 923, worm gear 921, pinion 911 to shift rack 906 and the blade and circle assembly transversely of the machine. Forward movement of control lever 1173 enables a clutch connection to shift the blade and circle assembly 70 to the left, while rearward movement of said lever 1173 enables a clutch connection to shift said blade and circle assembly to the right.

Shaft 1133 has universal joint 1206 with telescopic shaft 1207 which is connected by universal 75

5 joint 1209, including fork 954, to shaft 953. Said shaft 953 drives worm 952, worm gear 949, and pinion 942 to shift the circle on its center. Forward movement of control lever 1167 determines rotation of said circle in one direction, while rearward movement thereof determines rotation of the circle in the opposite direction.

10 Shaft 1153 has universal joint 1211 with telescopic shaft 1212, which is connected by universal joint 1214, including fork 1064, with shaft 1063 which is adapted to drive worm 1062 and worm gear 1061 of the scarifier lift mechanism in housing 1053. Thus it is seen that forward movement of control lever 1167 enables the drive 15 for lifting the scarifier, while rearward movement of said control lever enables the drive for lowering said scarifier.

15 Shaft 1176 has universal joint 1216 with telescopic shaft 1217 which has universal joint 1219, 20 including fork 867 (Fig. 13) with shaft 861 which drives bevel gear 859 and bevel gear 857 on collar 851 in housing 814 to operate lift screw 803. Control lever 1180 controls operation of the above described driving mechanism in the same manner that control lever 1187 controls operation of the 25 driving mechanism for lift screw 802, and can raise and lower the right end of the blade.

30 From the foregoing description, it is seen that the power control mechanism located at the operator's station, controls all adjustments of the blade and scarifier. The scarifier can be raised or lowered. The blade can be raised or lowered at either end by the telescopic lift hangers, the angle of the blade with respect to the line of draft can 35 be varied by rotating the circle about its center, and the blade can be positioned transversely with respect to the frame by operating the center shift mechanism.

The control levers for operating the above out-

lined adjusting mechanisms are arranged compactly on a control box located immediately in front of the operator above the clutch and brake pedals, and adjacent the steering wheel which is supported on the control box. The gear shift 5 lever is located immediately to the right of the control box which supports at its right end the ignition switch and the manifold heat control. The throttle control lever is mounted on the left end of the control box. Thus it is seen that all the 10 operating controls for the automotive road machine are located at the operator's station and are conveniently arranged to the operator so that a minimum of time and effort is required in operating the machine.

15

The reversible clutch mechanism in the control box is driven constantly from the crankshaft of the motor by a shaft extending through the clutch mechanism and forward to the control box. Thus a simple and direct drive is supplied to the 20 power control mechanism at all times, whether the machine be stopped or in motion.

I, therefore, claim as my invention:

In an automotive road machine, a frame, a motor mounted in said frame at the rear end 25 thereof, an earth engaging tool mounted on said frame forwardly of said motor, an operator's station between said tool and said motor, transmission means adjacent said motor, a hollow drive shaft extending forwardly from said motor, a 30 clutch between said motor and said hollow drive shaft, a drive connection between said hollow drive shaft and said transmission means, power control means for said tool at said station, and a drive shaft for said power control means having a constant drive connection with said motor and extending forwardly through said hollow shaft.

CARL A. GUSTAFSON.
